(57) **CLAIM**

The ornamental design for roller shade cassette cover, as shown and described.

DESCRIPTION

FIG. 1 is a front perspective view illustrating my design for a roller shade cassette cover;

FIG. 2 is a front perspective view thereof;

FIG. 3 is a right side view thereof;

FIG. 4 is a left side view thereof;

FIG. 5 is a top view thereof;

FIG. 6 is a top perspective view thereof;

FIG. 7 is a rear view thereof;

FIG. 8 is a rear perspective view thereof;

FIG. 9 is a bottom view thereof; and,

FIG. 10 is a bottom perspective view thereof.

The broken lines in the drawings are included for purposes of illustrating portions of the roller shade cassette cover, but form no part of the claimed design.

1 Claim, 10 Drawing Sheets
